SOAP DISPENSER

Carl A. Risher, Indianapolis, Ind.

Application February 28, 1950, Serial No. 146,863

5 Claims. (Cl. 299—83)

1

The present invention relates to new and useful improvements in soap dispensers and more particularly to automatic means for mixing powdered soap with water of a supply pipe for feeding a detergent solution to a hand or mechanical dish washer, or for other purposes.

The invention is designed primarily for use in the kitchens of hotels, restaurants and other establishments where large numbers of dishes must be quickly and thoroughly washed by mechanical or other means, and it is an object of the invention to automatically supply a soap solution to the washing machines in regulated amounts to most efficiently and economically accomplish the washing operation.

Another object is to connect the soap dispenser in the water supply pipe in a manner to entrain a soap solution with the flow of water and to deliver the same to a designated point.

A further object is to provide means for easily and quickly connecting a replaceable tank containing powdered soap in a water supply pipe whereby the water in any desired proportion may pass through the tank for mixing and discharging the soap with the water and without necessitating cutting off of the water supply to the pipe.

A still further object is to provide a pipe fitting for supporting and connecting a replaceable powdered soap container to a water supply pipe and including a spring loaded valve in the fitting held in closed position when the tank is removed therefrom and in which the valve is opened by the action of placing the tank in position on the fitting.

Another object is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a vertical sectional view of the replaceable tank shown connected to a water supply pipe, and

Figure 2 is an enlarged vertical sectional view of the fitting on which the tank is supported and showing the spring valve in closed position.

Referring now to the drawings in detail wherein for the purpose of illustration I have disclosed a preferred embodiment of my invention, the

numeral 5 designates a tank of predetermined capacity and having a pair of openings 6 and 7 in its bottom.

An inverted U-shaped tube 8 is attached at its ends in the openings, the tube preferably being constructed of a tube section 9 having a goose neck 10 connected to a straight tube section 11. The lower end of tube section 9 is connected in opening 6 by an internally and externally threaded stem 12 threaded in the opening and also threaded to the tube 9. Stem 12 is formed with a bulbous nipple 13 which projects downwardly from the bottom of the tank and in which a ball check valve 14 is housed. Openings or notches 15 are formed in the lower end of nipple 13. The lower end of tube section 11 is connected in opening 7 by an internally and externally threaded stem 16 on a downwardly projecting nipple 17 which also extends below the bottom of the tank. The upper end of straight tube section 11 is provided with a flared fitting 18 sleeved tightly over the end of goose neck 10 and an opening 19 is formed in one side of the lower portion of goose neck 10 with a bendable tongue 20 united at one end with the goose neck and inclined upwardly on the outside of the opening 19 to admit liquid into the tube 8 from the tank in regulated amounts and to form a deflector to prevent the flow in the outlet side of the tube from entering the tank.

A water supply pipe is shown at 21 to which a fitting, such as a T-fitting 22, is suitably connected and to which a conventional type of manual cut-off valve 23 is connected. A valve housing 24 is connected on top of valve 23 having an internal valve seat 25 against which a disc type valve 26 is held by a coil spring 27 forcing the valve 26 upwardly into closed position.

A tank support 28 is formed on top of valve housing 24 and includes a downwardly tapering passage 29 above valve seat 25 for receiving nipple 13 with a liquid tight fit, and a shelf structure 30 is formed at the top of valve housing 24 on which the tank rests.

In the operation of the device the valve 23 and tank support 28 are connected to a water supply pipe preferably in the manner illustrated in the drawings and a snap-on type faucet or hose is attached to nipple 17 to provide an outlet for the liquid passing through tube 8 to a dish washing machine (not shown) or to a sink or other receptacle for washing dishes by hand.

Soap powder 31 is placed in tank 5 in a predetermined amount and the tank is placed on shelf 30 of the tank support 28 and with the nipple 13

entering passage 29 to force valve 26 downwardly into its open position. Water from the supply pipe 21 then enters tube 8, the force or pressure of the water opening check valve 14.

The tube section 9 is formed with a plurality of orifices or nipples 32, one of which is positioned adjacent the lower end of the tube section 9 to loosen and prevent caking of the soap powder. The remaining nipples 32 are positioned above the level of the soap powder 31 to fill the upper portion of the tank with water and agitate the solution above the level of the soap to thoroughly dissolve the soap before entering tube 8.

As the pressure in the tank and tube 8 becomes equalized the flow of water through the tube will create a suction at opening 19 to draw the detergent solution in the upper portion of the tank into the tube to mix with the flow to thus automatically supply a washing solution to a desired point.

The alkalinity of the solution is regulated in accordance with the character of the water by constructing the tongue 20 at a desired angle with respect to opening 19 to increase or decrease the proportion of detergent solution entering tube 8. This may be done at the time of assembling the tube in the tank, and the tube may be easily removed from the tank by detaching nipples 13 and 17 to adjust tongue 20 and for refilling the tank with soap.

After the tank is supplied with soap and the tube 8 assembled therein, the tank is placed on support 28 and nipple 13 inserted in passage 29 of the support to engage and open valve 26 whereupon water enters the tube 8 from supply pipe 21 to fill the tank and dissolve the soap and the solution thus formed then passes through opening 19 and is carried to the dishwasher or other point of use with the water passing through the tube.

When the supply of soap in the tank is consumed the tank is lifted from support 28 and replaced by a replenished tank, and as the tank is lifted the valve 26 is automatically closed to cut off the water from passage 29 without interrupting flow of water through supply pipe 21.

Should supply pipe 21 be cut off or pressure therein reduced beyond a working point while the tank 5 is in position, check valve 14 will close nipple 13 to prevent the solution from draining back into the supply pipe to contaminate the water and the check valve 14 will also prevent dripping of solution from the nipple 13 during removal of the tank. A cross pin 31 in nipple 13 provides a stop for check valve 14 to prevent the latter from closing tube 8 when the valve is moved upwardly into its open position.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A soap dispenser comprising a tank adapted for containing a soluble detergent partially filling the tank, an inverted U-shaped tube in the

tank and having inlet and outlet ends, a fitting at each end of the tube projecting downwardly through and connected to the bottom of the tank and supporting the tube in an upright position in the tank, means connecting the fitting for the inlet end of the tube to a water supply, said tube having an opening in the tank adjacent its inlet end for feeding water into and dissolving the detergent and also having an opening above the level of the detergent to agitate the dissolved detergent, and a controlled port in the tube admitting dissolved detergent therein from the tank for entraining with the flow in the tube.

2. A soap dispenser comprising a tank adapted for containing a soluble detergent partially filling the tank, an inverted U-shaped tube in the tank and having inlet and outlet ends, a fitting at each end of the tube projecting downwardly through and connected to the bottom of the tank and supporting the tube in an upright position in the tank, means connecting the fitting for the inlet end of the tube to a water supply to provide an upflow side at the inlet end of the tube and a downflow side at the outlet end of the tube and disposed entirely within the tank, said upflow side of the tube having orifices filling the tank with water to dissolve the detergent and maintaining equalized pressure in the tank and tube, and said downflow side of the tube having an opening admitting dissolved detergent from the tank for entraining with the flow in the tube.

3. A soap dispenser comprising a tank adapted for containing a powdered detergent partially filling the tank, an inverted U-shaped tube in the tank and having inlet and outlet ends, a fitting at each end of the tube projecting downwardly through and connected to the bottom of the tank and supporting the tube in an upright position in the tank, means connecting the fitting for the inlet end of the tube to a water supply to provide an upflow side at the inlet end of the tube and a downflow side at the outlet end of the tube disposed entirely within the tank, said upflow side of the tube having orifices filling the tank with water to dissolve the detergent and maintaining equalized pressure in the tank and tube, and said downflow side of the tube having an opening admitting dissolved detergent from the tank for entraining with the flow in the tube, and means carried by the tube and concealed in the tank for regulating said last named opening to vary the proportion of detergent and water passing from the outlet of the tube.

4. A soap dispenser comprising a tank adapted for containing a powdered detergent partially filling the tank, an inverted U-shaped tube in the tank and having inlet and outlet ends projecting downwardly from the bottom of the tank, means connecting the inlet end of the tube to a water supply to provide an upflow side at the inlet end of the tube and a downflow side at the outlet end of the tube, said upflow side of the tube having orifices filling the tank with water to dissolve the detergent and maintaining equalized pressure in the tank and tube, and said downflow side of the tube having an opening admitting dissolved detergent from the tank for entraining with the flow in the tube, and a deflector on the tube and disposed exteriorly of the tube adjacent said last named opening to divert the downflow from the opening.

5. For use with a liquid supply pipe, a soap dispenser comprising a vertically disposed tubular member having a horizontal supporting flange at its upper end, a tank including a flat bottom

wall resting on and supported by said flange, a reversely bent tube positioned in the tank, extensions on the ends of said tube attached to and projecting downwardly from the bottom wall, and a valve in the tubular member preventing the passage of liquid from the tubular member prior to the placement of the tank upon the supporting flange, one of the extensions extending into the tubular member and engaging and retaining the valve in its open position, said tube having a plurality of openings therein to permit liquid passing through the tube to mix with and entrain detergent in the tank, said one of said extensions being located centrally of said bottom wall for centering said tank on said supporting flange. 15
